POTENTIOMETER

Carl F. Schaefer, Port Washington, N. Y., assignor to The Norden Laboratories Corporation, New York, N. Y., a corporation of Connecticut

Application December 10, 1948, Serial No. 132,235

15 Claims. (Cl. 201—48)

1

My invention relates to potentiometers or voltage dividers, and more particularly to an improved potentiometer in which voltage may be divided with improved accuracy.

A potentiometer depends for its accuracy upon the resistance element along which a brush is adapted to move. It is in essence a resistor connected across a potential with an adjustable arm adapted to adjustably contact the resistor. Many resistance elements for potentiometers comprise a winding of resistance wire such as nickel chrome alloy or the like upon the insulating base or core with which a movable brush is adapted to cooperate. The brush divides the resistance element into two segments and the lengths of the segments with respect to the terminals determine the manner in which the voltage is divided. It has been very difficult in practice to produce a potentiometer having linearity throughout and a desired overall voltage drop. It is possible to adjust fixed resistors to give a desired overall resistance within very narrow limits. A resistor, however, varies from segment to segment so that the resistance will not necessarily vary as a linear function of the movement of the brush over the resistance element. In many applications, such as in phase shifters and electronic computing instruments, it is extremely desirable to have a potentiometer which will have not only the desired overall resistance but in which resistance of the segments can be varied with greater accuracy in order to produce a linear function.

One object of my invention is to provide a potentiometer having the desired overall resistance within narrow limits and in which a predetermined movement of the variable brush will produce a corresponding change in resistance within very narrow limits.

Another object of my invention is to provide a potentiometer comprising a resistance element connected across a voltage source with a movable brush across which and one end terminal of the resistance element the output is removed in which a linear motion of the brush produces a corresponding linear change in potential, whereby voltage may be divided with great accuracy.

Other and further objects of my invention will appear from the following description.

In general my invention contemplates the division of the overall resistance of the potentiometer into a plurality of increments composed of fixed resistors divided into two groups. Each of the increments is adjusted to have the desired resistance within close limits. A pair of variable

2

resistors each having a pair of brushes adapted to embrace a resistance equal to one-half of the increments, is provided. The two pairs of brushes are moved in synchronism with each other and with a switch apparatus adapted to switch the fixed resistors from one group to the other at predetermined points. If the variable resistors are rheostats having circularly disposed resistors the brushes will be placed 180° apart and the switch will be switched from one group to the other after each 180° of movement of the pairs of brushes. The motion of the rheostat brushes is transmitted to a rotor adapted to connect the fixed resistance increments in series through a gear reduction having a predetermined ratio, so that connecting elements on the rotor advance to connect one adjacent pair of fixed resistance increments every 180° of movement of the rheostat brushes. The two rotors are connected to move together.

The arrangement is such that I need to accept only the non-linearity of a small fraction of the overall resistance, and in this way I am enabled to produce a potentiometer in which a voltage may be divided over a wide range with a high degree of accuracy.

In the accompanying drawings which form part of the instant specification and which are to be read in conjunction therewith, and in which like reference numerals are used to indicate like parts in the various views:

Figure 1 is a diagrammatic view showing a potentiometer containing one embodiment of my invention with one of the output segments being very small and the other being large, that is, with the parts in position near one extremity of adjustment.

Figure 2 is a diagrammatic view similar to Figure 1 showing the parts in position near the other extremity of adjustment.

Referring now to Figure 1, let us assume that the value of the resistance across the terminals of the potentiometer is represented by the expression

$$(2n+2) R + 2K$$

The terminals of the potentiometer are represented by binding posts 4 and 6 across which the potential is placed. The variable brush output is taken from binding post 8 and across either binding post 4 or binding post 6 or both. Expressed in terms of resistance, the resistance across 4 and 6 is constant while the resistance between 4 and 8 may be varied from zero to the full value of the resistance across the posts 4 and 6.

A first rheostat is provided with a circularly disposed resistance winding 19 adapted to be swept by a pair of brushes 12 and 14 mounted on a suitable insulating arm 16. The brushes 12 and 14 are 180° apart and are adapted to embrace the resistor 10 so that the value of the resistance between the brushes is R. In my copending application Serial No. 107,659 filed July 30, 1949, I have shown a variable resistor in which a pair of brushes sweeps a circularly disposed resistance element in combination with switching apparatus adapted to cumulatively place fixed resistors in series. In that application I have shown how the circularly disposed resistance element 10 may be displaced relative to the axis of rotation of the brushes to produce an overall resistance of R. A similar arrangement can be employed in the instant case. This adjustment will insure that the resistance along the resistor 10 between brushes 12 and 14 will have the pre-determined value R. A second circularly disposed resistor 16 is adapted to be swept by a pair of brushes 20 and 22 mounted upon an arm 24 connected to a rotatably mounted shaft 26 to which a knurled knob 28 is attached. The shaft 26 carries the insulating arm 16 for rotation therewith so that brushes 12 and 14 will rotate in unison with brushes 22 and 20. The value of the resistance along resistor 10 embraced by the brushes 20 and 22 is equal to R. Rotation of the arm 26 will rotate a shaft 30 which carries a gear 32 meshing with a larger gear 34 which in turn meshes with and drives a larger gear 36, which gear carries a shaft 38 secured to a drum 40. The arrangement is such that the drum 40 will rotate as a function of the rotation of the brush bearing arm 16, but at a much reduced speed due to the reduction gearing comprising gears 32, 34, and 36. The drum 40 is connected to a similar drum 42 by means of a shaft 46 so that drums 40 and 42 will rotate in unison. The rotation of shaft 26 will rotate a cam shaft 48 by any suitable drive (not shown) so that a cam 49 carried by the cam shaft 48 will rotate in phase with the brush arms 16 and 24 and at the same angular velocity. Mounted adjacent drum 40 I provide a group of fixed resistors 50, 52, 54, 56, and 58. Similarly adjacent drum 42 I mount a group of fixed resistors 60, 62, 64, 66 and 68. Each of the resistors 50, 52, 54, 56, 58, 60, 62, 64, 66, and 68 is accurately adjusted to have a resistance value of 2R. While I have shown five resistors associated with each of the drums, it is to be understood that any desired number of fixed resistors may be employed. Mounted upon the drum 40 for rotation therewith and spaced to connect the resistors in series, I provide a plurality of conducting bars 10, 12, 14, 16, and 18. A corresponding group of conducting bars 80, 82, 84, 86, and 88 are mounted on the drum 40 forming a second group of conducting bars separated from the first group of conducting bars by a pair of brushes 90 and 92. The brushes 90 and 92 are adapted to connect adjacent resistors of the resistors 50, 52, 54, 56, and 58 in series, depending upon the position of the brushes, in a manner similar to the connecting of the resistors in series by the conducting bars 10, 12, 14, 16, 18, 80, 82, 84, 86, and 88. The brushes, however, have a greater radius than the connecting bars and are adapted to contact contact points 94 and 96, the circuit across which is never completed by the conducting bars, due to the fact that the contact points 94 and 96 are placed out of the locus of the travel of the conducting bars.

The drum 42 is provided with a first group of conducting bars 98, 100, 102, 104 and 106. A second group of conducting bars 108, 110, 112, 114, and 116 are disposed upon the drum 42 separated by a pair of brushes 118 and 120. The brushes 118 and 120 of drum 42 correspond with brushes 90 and 92 of drum 40. In Figure 1 the brushes 118 and 120 are shown contacting contact points 122 and 124 which correspond to contact points 94 and 96. The contact points 122 and 124 are placed outside the locus of movement of the conducting bars 98, 100, 102, 104, 106, 108, 110, 112, 114 and 116. The conducting bars, however, are adapted to contact contact points 126 and 128 which correspond to contact points 88 and 90 associated with drum 40. The brush 90 is connected to a switch point 130 by conductor 132 and the brush 92 is connected to a switch point 134 by a conductor 136. The brush 118 is connected to a switch point 138 by conductor 140 and the brush 120 is connected to a switch point 142 by a conductor 144. A pair of switch arms 146 and 148 are pivotally mounted to rotate around pins 150 and 152. A link 154 is pivotally connected to arm 146 at point 156 and to arm 148 at point 158. The link 154 carries a cam follower 160 adapted to coat with the cam 48. A spring 162 urges the arms 146 and 148 to move to the right as viewed in Figure to bring the cam follower 160 in contact with the cam surface. The arm 146 carries a brush 162 which is connected by conductor 164 to a brush 166 carried by the arm 148. A conductor 168 connects the brush 166 to the binding post 6. A conductor 170 connects the binding post 4 to one end of the resistance winding 10. A conductor 172 connects the brush 12 to conductor 173 which is connected to the contact point 94. Conductor 172 is also connected to binding post 122. The brush 90 in the position shown in Figure 1 is connected by conductor 174 to the contact point 124. Contact point 94 is connected by conductor 176 to contact point 128 and contact point 126 is connected by conductor 178 to contact point 96. The brush 22 is connected to contact point 128 by conductor 176. Contact point 180 associated with drum 42 is connected to brush 14 by conductor 182 and a fixed resistor 184, the value of resistance of which is R. Similarly, the brush 20 is connected to contact point 186 by conductor 188 and fixed resistor 190 having a resistance value of R.

In operation, let us assume the parts are in the position shown in Figure 1. Let us trace the value of the resistance across binding posts 4 and 6. Starting from binding post 4 we follow conductor 170 through a segment of the resistance K to the brush 12. The path around the resistor 10 to the brush 14 through the resistor 186 through conductor 182 through the resistors 60, 62, 64, 66 and 68 through the conductor 178 is open at contact point 96. Following conductor 172 and 173 to contact point 94, thence through brush 92 through conductor 136 to switch point 134 brush 162 conductor 164 brush 166 switch point 130 conductor 132 brush 90, we arrive at resistor 50. It will be noted that resistor 50 is connected in series with resistor 52 by conducting bar 70 and the resistor 52 is connected in series with resistor 54 by conducting bar 72. Resistor 54 is in series with resistor 56 through conducting bar 74. Resistor 56 is in series with resistor 58 by conducting bar 76 and contact point 186 is in series with the resistors 75 by conducting bar 78. Since each of the resistors

50, 52, 54, 56, and 58 has a resistance value of $2R$ we have in addition to the K already noted a resistance value of $10R$. Following conductor 128 we pass through the resistor 188 having a value of R and thence to brush 20 and along the 5 rheostat resistance 118 to brush 22. The value of the resistance embraced between brushes 20 and 22 is R . From brush 22 we pass through the segment K of the resistor 18 and thence through conductor 171 to the binding post 8.

The resistance we have just traced can be expressed as $12R+2K$ which is the value of the resistance indicated above when n equals five. The resistance between binding post 4 and binding post 8 furthermore will be K which is the 15 only resistance embraced between these two points. It will be noted that the path from brush 22 to contact point 128 through conductor 178 is open and that the path through conductor 178 to contact point 98 is open. Let us now rotate the knob 28 in the direction of the arrow. As the resistance swept by brush 12 increases the resistance of rheostat 18 between brush 20 and point 21 on resistor 18 decreases a corresponding amount. The overall resistance, therefore, between points 4 and 8 is not varied. The resistance, however, between binding post 4 and binding post 8 is increased agreeable to the motion of the brush 12 in the clockwise direction. As the resistance increases both drum 48 and drum 42 will rotate at a reduced speed and in phase with the motion of the rheostat brushes. When brush 12 occupies the position of brush 16 in Figure 1, that is, when 180° of rotation of the brush bearing arms 16 and 24 has taken place, the cam 48 will have rotated from the position shown in Figure 1 to the position shown in Figure 2, and brush 22 will occupy the position occupied by brush 20 in Figure 1.

When this point arrives drum 42 will have rotated so that brush 120 will be in contact with contact point 180, brush 118 will be in contact with the end of resistor 60, conducting bar 98 will be in a position to connect resistors 60 and 62 in series, conducting bar 100 will be in a position to connect resistors 62 and 64 in series, conducting bar 102 will be in a position to connect resistors 64 and 66 in series, conducting bar 104 will be in a position to connect resistors 66 and 68 in series, and conducting bar 106 will be in a position connecting contact points 126 and 128. The contact made by the conducting elements carried by the drum 48 in Figure 1 will be near the point of being broken. It makes little difference, however, whether they are broken or not since the switch brushes 162 and 166 will disconnect these from the circuit on the operation of the cam. Inasmuch as both rotors and their associated rheostats will always register the same resistance and the brushes will always be located at the same relative point in the overall resistance, it is not necessary that the switching take place at any critically exact moment. The exact relationship between the position of the brushes and the point of switching is difficult to control in operation, but in the arrangement I have shown the correct resistance will always be included between the terminals 4 and 8 and the correct resistance will always be registered irrespective of differences in the path of travel of the brush arms 16 and 24 with respect to the point at which switching takes place.

At points of maximum and minimum adjustment of the variable potentiometer arm, it will

be necessary to register zero and maximum on both rotors independent of whether the switch connects one rotor or the other to the terminal 8. I will point out how I have avoided a critical point of switching at the terminal points of adjustment hereinafter.

Let us now trace the overall resistance between binding posts 4 and 8. From binding post 4 we follow conductor 170 through the segment of resistor 18 of the value of K to brush 14 through resistance 184 of the value of R through conductor 182 to contact point 180 to brush 120, which is now in contact with this contact point, through conductor 164 to contact point 142 through brush 166, which is now in contact with this contact point, through conductor 184 through brush 162, which is now in contact with contact point 138, through conductor 148 to brush 118, which is now in contact with the end of resistor 60, thence through conducting bar 98 through resistor 62 through conducting bar 100 through resistor 64 through conducting bar 102 through resistor 66 through conducting bar 104 through resistor 68 through conducting bar 106 to contact point 128, thence through conductor 178 to brush 22 through the resistance 18 through conductor 171 to binding post 8. It will be seen that the overall resistance, therefore, has not varied. The resistance between binding post 4 and binding post 8, however, is now $R+K$, the R being introduced by the resistor 184 and the K between binding post 168 and the position of the brush 14.

As motion is continued in the direction of the arrow in Figure 1, the value of the resistance between brush 22 and binding post 8 will continue to decrease while the value of the resistance between brush 14 and resistance terminal 168 will continue to increase by a like amount.

40 By the time brushes 12 and 22 reach the positions shown in Figure 1 and the cam is ready to operate, the switch brushes 90 and 92 will be bridging the gap between the resistors 50 and 52. Conducting bar 80 will occupy the position shown by the brushes 90 and 92 in Figure 1. Conducting bar 78 will be connecting resistors 52 and 54 in series. Conducting bar 72 will be connecting resistors 54 and 56 in series, conducting bar 74 will be in a position connecting resistors 56 and 58 in series, and conducting bar 76 will be connecting the end of resistor 58 with contact point 186. Conducting bar 78, however, will not connect contact points 94 and 96, as these are contacted only by brushes 90 and 92. Similarly, 55 with respect to drum 42, the contact points 124 and 122 will not be contacted by conducting bar 108.

The action just described will continue. The resistance between binding post 4 and terminal 00 8 is gradually increased by either resistor 10 or 18 and its coating brushes and the increase of resistance represented by the sweep of the brushes being cumulated by the fixed resistors and the switching apparatus until the parts have reached 65 the position shown in Figure 2.

As the knurled knob 28 is continued being rotated in a clockwise direction the same action occurs. The brushes 92 and 90 of rotor 40 and the brushes 120 and 118 of rotor 42 being advanced in phase with each other and having a predetermined relationship to the rotation of the brush bearing arms 16 and 24, the overall resistance remains the same and the terminal 8 is alternately switched from one rotor brush to the 70 other in step by step fashion. There is a slight

overlap in the period of time that the brushes and conducting bars remain in contact. To take a simple case, near the point at which the switch should work the conducting bar 70, for example, will be bridging resistors 50 and 52 for a short period after conducting bar 98 of rotor 42 has completed the circuit between resistors 60 and 62. To continue the action during the time while conducting bar 98 is bridging the circuit between resistors 60 and 62 associated with rotor 42 the conducting bar 70 will have reached a position to connect resistors 52 and 54 associated with rotor 40. In this manner if the switching takes place a little before it should the correct resistance value will be registered at terminal 8. Similarly, if there is a little lag at the switching point the correct resistance value will still be registered at terminal 8. This action is not at all critical because of this construction during the major portion of the movement. At a point when the terminal 8 is to be connected to terminal 4 (zero value) and at a point when terminal 8 is connected to terminal 6 (maximum value) I am enabled to avoid the critical adjustment at the extreme points by means of two auxiliary contact points 94 and 96 associated with rotor 40 and 122 and 124 associated with rotor 42.

Let us assume, further, that we do not know for certain whether the switch will be in the position shown in Figure 1 or in the position shown in Figure 2. If the switch is in the position shown in Figure 1 no difficulty is experienced since point 4 is connected to point 8 through conductor 170 brush 12 conductor 172 conductor 173 brush 92 conductor 186 contact point 134 switch arm 162 conductor 164 to conductor 168. At the same time the resistance between the terminals 4 and 6 will be measured through a circuit completed by switch arm 166 contact point 130 contact point 132 brush 90 resistors 50, 52, 54, 56 and 58, and their intermediate conducting segments, conductor 188 resistor 190 brush 20 and a resistance value along the resistor 18 equal to $2K+R$ to conductor 171 to terminal 6. Let us suppose, however, that at this point the switch instead of being in the position shown in Figure 1 is actually in the position shown in Figure 2, the circuit can not be completed through brushes 90 and 92 since the gap between contact points 134 and 130 is open. The circuit path may now be traced as follows: from conductor 172 to contact segment 122 through conductor 144 to contact point 142 through the switch brush 166 through connecting conductor 164 through the switch arm 162 to contact point 138 through conductor 140 through brush 118 through conductor 174 and thence through the resistors 50, 52, 54, 56, and 58 through conductor 188 through resistor 190 and the resistance winding 18 through conductor 171 to the terminal 6. Due to the use of the auxiliary contact points 122 and 124 which are closed only by the brushes 118 and 120 and never by any of the conducting bars on rotor 42, I am enabled to achieve the zero position irrespective of the position of the cam operated switch. It will be noted further that contact points 126 and 128 are always open near the zero position so that the resistances of rotor 42 do not come into play.

Referring now to Figure 2, I have shown the same arrangement adjacent the maximum point. Let us rotate the brush 22 to bring it into contact with the conductor 171 at point 21. If the switch does not operate to move from the position shown in Figure 2 until contact is made between brush 22 and the point 21, terminal 8 is at maximum

voltage through conductor 171 brush 22 conductor 178 contact point 128 brush 118 conductor 140 contact point 130 brush 162 conductor 164 and conductor 168. The circuit, furthermore, between terminal 6 and terminal 4 is completed through brush 166 conductor 164 brush 120 contact point 126 resistors 68, 66, 64, 62 and 60, conductor 162 resistor 184 brush 14 and a resistance along resistor 18 equal to $2K+R$, and thence through conductor 170 to terminal 4. If, however, the rotary movement of the brush 22 past the position occupied by brush 20 causes the cam 48 to throw the switch to the position shown in Figure 1, terminal 8 is placed at the potential of terminal 6 through the path comprising conductor 171 brush 22 conductor 178 contact segment 94 brush 90 conductor 182 switch point 130 and switch arm 166. The resistance path across the potentiometer is completed through conductor 164 switch arm 162 switch point 134 conductor 186 brush 92 contact point 96 conductor 176 through resistors 68, 66, 64, 62 and 60, and thence through conductor 162 resistor 184 brush 14 and the resistance winding 18 to conductor 170 and terminal 4. In this case it will be noted that contact points 94 and 96 are open, there being no conducting bar adjacent these contacts near the maximum position.

It will be clear from what has been said that a zero point and a maximum point can always be reached irrespective of the position of the switch at these points. At intermediate points of travel of my potentiometer the switching is likewise not critical because the correct value of the resistance between terminals will always be registered whether the path is through the resistors associated with rotor 40 or through the resistors associated with rotor 42. Similarly, the terminal 8 will always be at its correct adjustment so that there will be no change in value whenever the switching does take place. It is understood, of course, that the switch arrangement shown is diagrammatic only and that a quick acting switch will be employed to minimize the momentary interruption of the circuit which takes place during the switching.

It will be noted that in operation the brushes 92 and 90 will rotate successively connecting adjacent resistors associated with drum 40 and the brushes 118 and 120 will rotate successively connecting intermediate resistors associated with drum 42. Taking contact points 91 and 89 as an example, these will be bridged first by the brushes 92 and 90. The circuit will next be completed across contact point 180 and the end of resistor 60 by the brushes 120 and 118. The circuit will next be completed across contact points 89 and 91 by conducting bar 80. The circuit will next be completed across contact point 180 and end of resistor 60 by conducting bar 108. The action thus continues stepwise until the maximum is reached as described above.

It will be seen that I have accomplished the objects of my invention. I have provided a potentiometer which will have the desired overall resistance between narrow limits and in which a predetermined movement of the variable brush will produce a corresponding change in resistance within very narrow limits. I have provided a potentiometer in which voltage may be divided with a great linearity as a function of movement of the variable potentiometer brush. Due to the fact that the rheostats employed represent only a small fraction of the overall resistance a very minor error is introduced. These rheostats, fur-

thermore, can be selected for the linearity and a very accurate overall system is produced.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

1. A potentiometer including in combination a pair of terminals, a resistance across the terminals comprising a plurality of separated fixed resistors and a rheostat having a variable brush, a multiple element switch for connecting the fixed resistors and the rheostat in series, a third terminal, means for connecting one of said switch elements to the third terminal and means for moving the switch in predetermined relation to the movement of the rheostat brush whereby the switch element connected to the third terminal will successively bridge successive fixed resistors.

2. A potentiometer including in combination a pair of terminals, a resistance across the terminals comprising a pair of rheostats each having a pair of brushes adapted to intercept a predetermined resistance, means for rotating said rheostat brushes in unison, two groups of fixed resistors associated with respective rheostats each resistor of which has a resistance equal to twice the predetermined resistance intercepted by the rheostat brushes, a pair of multiple element switches adapted to connect resistors of a respective group in series with each other and with one of the rheostat brushes, one of the elements of each of the multiple element switches comprising a pair of brushes, a double pole switch for alternately connecting the element brushes of one or the other of said multiple element switches, means for connecting the last resistor of each group of resistors to the other rheostat brush associated with the other group of resistors, means for moving the multiple element switches in unison and at a predetermined function of the movement of the rheostat brushes, means for operating said double pole switch from a position bridging one pair of element brushes to a position bridging the other pair of element brushes alternately after a substantially predetermined movement of the rheostat brushes in a given direction, a third terminal for the potentiometer, and means for connecting a switch arm of said double pole switch to said third terminal.

3. A potentiometer as in claim 2 in which each of said means for connecting the last resistor of each group of resistors to the other rheostat brush includes a fixed resistor having a resistance value equal to that intercepted by the rheostat brushes.

4. A potentiometer as in claim 2 in which said means for operating said double pole switch comprises a cam and means for actuating said cam as a function of the movement of the rheostat brushes.

5. A potentiometer as in claim 2 including means for interconnecting the element brushes in parallel adjacent points of minimum and maximum positions of the multiple element switches whereby the one or the other of said

first two terminals will be connected to the third terminal irrespective of the position of the double pole switch at maximum and minimum setting.

6. In a voltage divider a pair of rheostats each having a resistance element, a pair of movable brushes each adapted to traverse respective resistance elements to vary the resistance between the brush and one end of the resistance element, means for moving said brushes in unison, a plurality of groups of fixed resistors each resistor of which has a predetermined resistance value, a pair of multiple element switches each associated with one group of fixed resistors adapted to connect the fixed resistors of one group in series with each other and with the rheostats, one element of each of said respective multiple element switches comprising a pair of brushes, means for moving said multiple element switches as a function of the movement of the rheostat brushes whereby to successively connect different resistors of a group to each other by means of a pair of brushes, and switching means adapted alternately to bridge the brushes as a function of the movement of the rheostat brushes.

7. A voltage divider as in claim 6 in which the rheostat resistance elements are so disposed that when the first brush increases the resistance between the end of the resistor and the brush the second brush will reduce the resistance between the brush and the end of the rheostat resistance by the same amount.

8. A voltage divider as in claim 6 in which each of said rheostats is provided with respective second brushes, means for mounting said second brushes to move in unison with said first brushes to intercept a predetermined resistance value, said resistance value being one-half of the resistance of each resistor of said groups of fixed resistors.

9. A voltage divider as in claim 6 in which each of said rheostats is provided with respective second brushes, means for mounting said second brushes to move in unison with said first brushes to intercept a predetermined resistance value, said resistance value being one-half of the resistance of each resistor of said groups of fixed resistors, and means for connecting the second brush of one rheostat to the last resistor of the group of fixed resistors associated with the other rheostat.

10. A voltage divider as in claim 6 in which each of said rheostats is provided with respective second brushes, means for mounting said second brushes to move in unison with said first brushes to intercept a predetermined resistance value, said resistance value being one-half of the resistance of each resistor of said groups of fixed resistors, means for connecting the second brush of one rheostat to the last resistor of the group of fixed resistors associated with the other rheostat, said means including a fixed resistor having a resistance value equal to that intercepted between the rheostat brushes of a rheostat resistance.

11. A potentiometer including in combination a pair of terminals, a pair of rheostats having circularly disposed resistors, a pair of brushes associated with each rheostat resistance element adapted to intercept a predetermined resistance value, means for connecting one terminal to one end of one of the rheostat resistors, means for connecting the other terminal to one end of the other of said rheostat resistors, a first group of separate fixed resistors each having a resistance value equal to twice the resistance intercepted by

the rheostat brushes and associated with one of said rheostats, a second group of fixed resistors associated with the other of said rheostats each resistor of which has a resistance equal to twice the resistance intercepted by the rheostat brushes, a rotary switch member associated with said first group of resistors, said rotary member having a plurality of switching members adapted to connect the fixed resistors in series, one of said switching elements comprising a pair of brushes, means for connecting said brushes to two poles of a double pole double throw switch, a second rotary member associated with the second group of fixed resistors having switching elements adapted to connect the fixed resistors in series, one of said switching elements comprising a pair of brushes, means for connecting said brushes to another pair of poles of the double pole double throw switch, a contact point separated from the first resistor of the first group of fixed resistors, means for connecting the contact point to one of the brushes of the first rheostat, a second contact point spaced from the end of the last resistor of the first group of resistors, means for connecting the second contact point to one of the brushes of the second rheostat, a contact point spaced from the last resistor of the second group of resistors, means for connecting this contact point to the second brush of the second rheostat, a contact point spaced from the first resistor of the second group of resistors, means for connecting this contact point to the second brush of the first rheostat, said contact points being adapted to be connected to adjacent resistors by means of said rotary switch elements, means for rotating said

rheostat brushes in unison, means for rotating said rotary switch members in predetermined phase relation with each other and with the movement of the rheostat brushes, means for operating said double pole double throw switch as a function of movement of the rheostat brushes whereby alternately to place resistors of one group of fixed resistors in series with the rheostat resistances across the pair of terminals of the potentiometer, a third terminal, and means for connecting the third terminal to one or the other of said brush switch elements.

12. A potentiometer as in claim 11 in which said means for connecting the second contact point of the first group of resistors to one of the brushes of the second rheostat includes a fixed resistor having a resistance equal to that intercepted by the rheostat brushes.

13. A potentiometer as in claim 11 in which said means for connecting the contact point spaced from the first resistor of the second group of resistors to the second brush of the first rheostat includes a fixed resistance having a resistance value equal to that intercepted by the rheostat brushes.

14. A potentiometer as in claim 11 in which said rheostat brushes are disposed substantially 180° apart.

15. A potentiometer as in claim 11 including in combination means for connecting said rotary brush switch elements in parallel at positions of minimum and maximum adjustment.
